H. C. Lord,
ATTORNEY.

UNITED STATES PATENT OFFICE.

FREDERICK OSSIAN BALL, OF PLAINFIELD, NEW JERSEY.

LUBRICATING DEVICE FOR ECCENTRICS.

SPECIFICATION forming part of Letters Patent No. 611,854, dated October 4, 1898.

Application filed January 8, 1898. Serial No. 666,027. (No model.)

To all whom it may concern.

Be it known that I, FREDERICK OSSIAN BALL, a citizen of the United States, residing at Plainfield, in the county of Somerset and 5 State of New Jersey, have invented certain new and useful Improvements in Lubricating Devices for Eccentrics; and I do hereby declare the following to be a full, clear, and exact description of the invention, such as will 10 enable others skilled in the art to which it app pertains to make and use the same.

This invention relates to lubricating devices for eccentrics; and it consists in certain improvements in the construction thereof, as 15 will be hereinafter described, and pointed out in the claims.

More particularly, my invention relates to the eccentric mechanism of automatic cut-off engines and the means for supplying oil to 20 said mechanism.

The invention is illustrated in the accompanying drawings, as follows:

Figure 1 shows a view of the eccentric mechanism, partly in elevation and partly in 25 section. Fig. 2 is a section on the line 22 in Fig. 1.

A marks the shaft upon which the eccentric mechanism is mounted, usually the crank-shaft of an engine; B, a frame secured to the 30 shaft; C, the pin on which the eccentric is pivoted, said pin having the extension C' projecting through a portion of the frame B; C², a nut on the extension C' for securing it in place; D, the eccentric, and E the eccentric-strap. The eccentric is provided with the 35 usual slot around the shaft A, so that it is free to swing on the pivot formed on the pin C. A governor or other device (not shown) is usually provided for controlling the swing 40 of the eccentric on the pivot-pin C, and as the throw of the eccentric is changed by a change of position of the eccentric on its pivot the throw of the eccentric is thus controlled.

The eccentric-pin C has a longitudinal duct 45 c and radial ducts c', leading from the duct c to the surface of the pin. A brass bushing D' is placed in the eccentric, and a circumferential groove c² either in the bushing or the eccentric-pin (shown in the pin) connects the 50 several ducts c with the ducts d in the bushing. A longitudinal groove c³ facilitates the distribution of oil for the bearing on the pin

C. A circumferential groove d' either in the bushing or eccentric (shown in the bushing) connects the several ducts d with the duct d², 55 which leads to the eccentric-bearing.

An oil-receptacle F of annular form encircles the shaft and is secured by screws f to the pin C. The cavity F of the receptacle is somewhat eccentric to the shaft, and at the 60 point the most remote from the axis a duct f' connects the cavity with the duct c.

The outer flange of the receptacle is far enough from the shaft to allow the introduction of the tube g, leading from the oil-cup G. 65

In operation the oil is dropped into the receptacle and is carried by centrifugal force into and through the ducts f' c c' to the pivot-bearing, which is thus lubricated, and thence by the groove c², duct d, groove d', and duct 70 d² to the eccentric-bearing. Of course it will be understood that if the outwardly-extending duct c' is in register with outward duct d very little, if any, oil will flow circumferentially in the groove c², and if care is taken to 75 get the bushing D' so positioned in the eccentric as to bring the duct d into register with the duct d² the groove d' may be dispensed with. I prefer, however, the construction having the circumferential grooves, as the 80 assembling of parts are thus much simplified.

What I claim as new is—

1. In a lubricating device for eccentrics, the combination with the eccentric-shaft; and a frame secured to said shaft; of a pin secured to said frame; an eccentric pivoted on said pin; a strap on said eccentric; and an oiling mechanism arranged to conduct oil to the pivot-bearing and from the pivot-pin to the eccentric-bearing. 85

2. In a lubricating device for eccentrics, the combination with the eccentric-shaft; and a frame secured to said shaft; of a pin secured to said frame; an eccentric pivoted on said pin; and an annular oil-receptacle secured to said pin and encircling the shaft, said receptacle and pin being provided with ducts leading from the receptacle to the pivot-bearing. 95

3. In a lubricating device for eccentrics, the combination with the eccentric-shaft; and a frame secured to said shaft; of a pin secured to said frame; an eccentric pivoted on said pin; a strap on said eccentric; and an

annular oil-receptacle secured to said pin and encircling the shaft, said receptacle, pin and eccentric being provided with ducts connecting the receptacle with the pivot-bearing and 5 the pivot-bearing with the eccentric-bearing.

4. In a lubricating device for eccentrics, the combination with the eccentric-shaft; and a frame secured on said shaft; of the pin, C, secured to said frame and having the ducts, 10 c, c'; the eccentric pivoted on said pin and

having the duct, d², said eccentric and pin having a circumferential groove connecting ducts, c' and d², a strap on said eccentric; and means of supplying oil to the duct, c.

In testimony whereof I affix my signature 15 in presence of two witnesses.

FREDERICK OSSIAN BALL.
